UNITED STATES PATENT OFFICE.

WALTER J. BAKER, OF CHICAGO, ILLINOIS.

DESIGN FOR A COMBINED CIGARETTE HOLDER AND CAP.

Application filed July 19, 1928. Serial No. 27,527. Term of patent 7 years.

To all whom it may concern:

Be it known that I, WALTER J. BAKER, a citizen of the United States, residing at Chicago, in the county of Cook and State of Illinois, have invented a new, original, and ornamental Design for a Combined Cigarette Holder and Cap, of which the following is a specification, reference being had to the accompanying drawing forming a part thereof.

The figure is a view in front elevation of a combined cigarette holder and cap showing my new design.

I claim:

The ornamental design for a combined cigarette holder and cap, as shown.

WALTER J. BAKER.
